[57] CLAIM

The ornamental design for a spacer for boards in vertical or oblique position, as shown and described.

DESCRIPTION

FIG. 1 is a top plan view of a spacer for boards in vertical or oblique position showing my new design;
FIG. 2 is a left side elevational view thereof;
FIG. 3 is a front elevational view thereof;
FIG. 4 is a bottom plan view thereof;
FIG. 5 is a right side elevational view thereof;
FIG. 6 is a left side sectional view taken on the line 3A—3A of FIG. 3;
FIG. 7 is a sectional view taken on the line 3B—3B of FIG. 3;
FIG. 8 is a front elevational view thereof in an operative position with an environmental structure of boards, shown in broken lines for illustrative purposes only, and forming no part of the design claimed;
FIG. 9 is a front, top and right side perspective view thereof; and
FIG. 10 is a front, bottom and left side perspective view thereof.

FIG. 1

FIG. 2

FIG. 3

FIG. 4

FIG. 5

FIG. 6

FIG. 7

FIG. 8

FIG. 10

FIG. 9
